UNITED STATES PATENT OFFICE.

SAMUEL JOSEPH HARRIS, OF LAKE CITY, FLORIDA.

SWITCH.

SPECIFICATION forming part of Letters Patent No. 703,917, dated July 1, 1902.

Application filed January 14, 1902. Serial No. 89,769. (No model.)

To all whom it may concern:

Be it known that I, SAMUEL JOSEPH HARRIS, a citizen of the United States, residing at Lake City, in the county of Columbia and State of Florida, have invented new and useful Improvements in Switches, of which the following is a specification.

My invention relates to split switches, and contemplates the provision of a safety appliance therefor calculated to insure the absolute safety of the main track at all times, even in the event of the heel-bolt in the switch-stand or the bolt between the connecting-rod and tie-bar dropping out of place, the switch-stand being knocked down by a passing train or any other accident occurring to the switch-shifting apparatus. The improved appliance is also calculated to compensate for the lost motion in the throw of a switch due to the wear of the connecting-bolts, and thereby remove the liability of a wheel having a sharp flange or a deranged truck taking the siding and causing a wreck.

With the foregoing in mind the invention will be fully understood from the following description and claim when taken in conjunction with the annexed drawings, in which—

Figure 1 is a plan view of a switch equipped with my improved safety appliance; Fig. 2, an enlarged detail section taken in the plane indicated by the line 2 2 of Fig. 1; Fig. 3, a plan view showing the base-plate, casing, and thrust-rod of the appliance; Fig. 4, a detail transverse section taken in the plane indicated by the line 4 4 of Fig. 2, and Fig. 5 a similar view taken in the plane indicated by the line 5 5 of Fig. 3.

Similar letters of reference designate corresponding parts in all of the several views of the drawings, referring to which—

A is one rail of the main track; B C, the opposite rails thereof; D, one rail of the siding; E, the other siding-rail, which merges into the main-track rail B; F, one of the switch-points, which abuts at its heel against the end of rail D and is adapted to be thrown against the rail A; G, the other switch-point, which abuts against the end of the rail C and is arranged to be shifted against the rail B to render continuous one side of the main track; H, a tie-bar connected to the switch-points, and I a connecting-rod designed to extend to

a switch-stand, which I have deemed it unnecessary to illustrate. These several parts may be and preferably are of the ordinary construction.

In the preferred embodiment of my invention the safety appliance comprises a base-plate J, arranged on and connected to one of the sleepers or ties in a position adjacent to the point G; a cylinder K, connected to the base-plate in a position at right angles to point G and having its end adjacent to said point open and its end remote from the same provided with a central aperture a; a thrust-rod L, having its rear end disposed in the aperture a of the casing and its forward end seated in a socket M, connected to the inner side of the point G and also having a collar b at an intermediate point of its length, snugly fitting and movable in the bore of the casing, and a coiled spring N, preferably of steel, contained in the casing and surrounding the thrust-rod and interposed between the collar b of the same and the rear end of the casing. The said spring obviously tends at all times to thrust the rod L forwardly—i. e., in the direction indicated by arrow in Fig. 2—and consequently it will be seen that the appliance will not only take up all lost motion in the working parts, so as to insure the point G lying tight against the rail B when the switch is set for a clear main track, and thereby prevent a sharp flanged wheel or a deranged truck from taking the siding, but will also press and hold the point against the rail B and insure an absolutely safe main track in the event of the switch-stand being broken or the parts thereof becoming casually disconnected.

The collar b, fitting snugly in the bore of the cylinder K, assists the aperture a in guiding the rod L and precludes movement of the rod and spring in any but an endwise direction, with the result that the spring is better able to hold the point G in and return it promptly to the position shown.

By virtue of the socket M it will be observed that my improvements are susceptible of ready application to switch-points such as at present in use, which is an important advantage.

While I prefer to use my improvements in conjunction with the kind of switch illus-

trated, and specifically described in the foregoing, I do not desire to be understood as confining myself to the same, as the improvements may be used to advantage in connection with any kind of switch to which they are applicable.

Having described my invention, what I claim, and desire to secure by Letters Patent, is—

- 10 1. The herein-described safety appliance for switches consisting essentially of the casing having a smooth bore, and also having its forward end open, and its rear end provided with a central aperture, the rod for exerting thrust against a switch-point, formed of one piece of material and disposed in the casing with its rear end guided in the central aperture of the casing, and having the integral collar at an intermediate point of its length snugly fitting and movable in the smooth bore of the casing, and the coiled spring surrounding the rod within the casing and interposed between the integral collar of the rod and the rear end of the casing.
- 15 2. The combination of the switch-point
- 20
- 25

having the socket at one side, the casing disposed at right angles to the point, and having a smooth bore, and also having its forward end open, and its rear end provided with a central aperture, the rod for exerting thrust ³⁰ against the switch-point having its forward end arranged in the socket on the point; the said rod being formed of one piece of material, and being disposed in the casing with its rear end guided in the central aperture there- ³⁵ of, and having the integral collar at an intermediate point of its length snugly fitting and movable in the smooth bore of the casing, and the coiled spring surrounding the rod within the casing and interposed between the integral collar of the rod and the rear end of the casing.

In testimony whereof I have hereunto set my hand in presence of two subscribing witnesses.

SAMUEL JOSEPH HARRIS.
